WINDOW OPERATOR

Robert L. Fahs, Fairborn, and Willard N. Miller, Troy, Ohio, assignors to Philips Industries, Inc., Dayton, Ohio, a corporation of Ohio

Filed Feb. 27, 1968, Ser. No. 10,750

Term of patent 14 years

(Cl. D10—10)

FIG. 1.

FIG. 3.

FIG. 2.

FIG. 4.

FIG. 5.

FIG. 1 is a front-elevational view of the window operator;

FIG. 2 is a rear-elevational view thereof;

FIG. 3 is a plan view thereof;

FIG. 4 is a side-elevational view thereof; and

FIG. 5 is a perspective view thereof.

The side opposite from that shown in FIG. 3 is identical to the side shown in FIG. 3.

We claim:

The ornamental design for a window operator, substantially as shown and described.
